*J. Cochrane,
Pump Lift*

No 10,306.

Patented Dec. 13, 1853.

UNITED STATES PATENT OFFICE.

JAMES COCHRANE, OF NEW YORK, N. Y.

HYDRANT-VALVE.

Specification of Letters Patent No. 10,306, dated December 18, 1853.

To all whom it may concern:

Be it known that I, JAMES COCHRANE, of the city, county, and State of New York, have invented a new and useful Improvement 5 in Hydrants for Drawing Water, of which the following is a full, clear, and exact description, reference being had to the accompanying drawings, making part of this specification, in which—

10 Figure 1 is front elevation as attached to ordinary hydrants. Fig. 2 is a plan with hydrant, discharge pipe, &c., removed. Fig. 3 is a central section of discharge pipe, cock, and cock plug, expanding chamber, flexible 15 substance, plate H and semisphere, in position of having the water suspended in the discharge pipe.

The same letters indicate like parts in all the figures.

20 To prevent the water from freezing during cold weather in the discharge pipe of hydrants the ordinary practice has been to provide the discharge pipe with a waste hole and cock or valve which is usually 25 closed while drawing water and then opened to permit the contents of the discharge pipe to escape or waste; and although this generally prevents the water from freezing, in the discharge pipe, yet it is seriously ob- 30 jectionable, for the reason that it occasions a great waste of water, particularly in populous cities; and the water thus wasted below the surface of the ground soaks or drains through the earth, and gradually 35 washes away the earth, or sand, surrounding the foundations, of houses in the neighborhood, thereby rendering them weak and damp.

The object of my invention is to remedy 40 these objections and also to make the hydrant self closing by the hydrostatic pressure and gravity of the ordinary waste water; and to this end it consists in combining, with the discharge pipe, of hydrants, 45 a contracting and expanding chamber, which is expanded when the main valve of the hydrant is being closed, by the ordinary waste water running or falling therein from the discharge pipe, to protect it from the 50 frost; and contracted or emptied, before, or at the time the main valve, or cock, is opened, to force the water back into the discharge pipe. In this way I am enabled effectually to keep the water out of the dis- 55 charge pipe, and so far below the surface, as to prevent freezing, and without the

waste of water, with the inconveniences attendant thereon, and also make the hydrant self closing, by the force of the water, leaving the discharge pipe.

60 In the accompanying drawings S represents the main pipe leading from the head of water to the chamber of cock E containing the plug which governs the delivery of water to the discharge pipe I, extending 65 above the surface. The main valve or cock plug, which is rotary, is provided with a crank arm, and joint pin, connected by link L, to a joint pin, projecting from a forked sliding cross frame C, which frame is attached to rod D, with a handle or lever V above the surface, by which the cock plug, or valve is moved, to open and close the 70 passage, for water from the main, to the discharge pipe.

75 The lower end of the discharge pipe communicates with a chamber or vessel B, below of sufficient capacity to contain as much or more than the discharge pipe; and the bottom of this chamber is a flexible disk, 80 R, of vulcanized india rubber, or other flexible substance, properly secured as by plate H, to the lower edge or bottom flanch. This flexible bottom should be dished; and below it there is a semisphere A, attached 85 to the enlarged lower ends of sliding cross frame C and moving with it, so that when the hand lever V is lowered, to turn the valve or cock, to shut off the water from the discharge pipe, the semisphere A, is let 90 down so that the water in the discharge pipe can descend into the chamber or vessel B, the flexible disk yielding to the pressure of the column of water, and impinging 95 on the semisphere, and by that force, on the sliding cross frame, and link connecting to crank arm of cock plug, forms thus, the closing force; and when the handle is raised to draw water, the semisphere A is drawn 100 up which forces the flexible disk into the chamber, or vessel, thereby contracting it, and forcing the water out of it back into the discharge pipe. The same motion causes the water way in cock plug to coincide with the main and discharge pipes. In this way 105 the hydrant is operated, and the water is kept below the reach of frost, without waste, avoiding all the inconveniences, heretofore experienced. If however, the valve or cock by wear should leak, the chamber or vessel 110 would soon overflow, and the water would then rise in the discharge pipe, and be ex-

posed to frost. To prevent this I make a small waste hole X, which communicates with the lower end of the discharge pipe; and I also make a small way Y in the valve or cock, which opens the communication between the discharge pipe, and this waste hole, when the main valve is closed and the expanding chamber nearly wholly expanded, so that any water leaking through the main valve, or cock, will be discharged, or wasted; and the moment, the valve or cock is moved, to draw water, the waste hole is closed to prevent the escape of water.

I have thus pointed out the nature of my invention, and the mode of application which I have tried with success; but I do not wish to be understood as limiting myself to this particular mode of application as other modes may be devised having the same principle or mode of operation, as for instance, instead of the flexible chamber a piston and chamber may be substituted, or any known mode of reducing and enlarging the capacity of the chamber or alternately admitting and forcing the water therefrom may be substituted, and so with reference to the valve, any other mode of closing and opening the passage between the main and

the discharge pipe, such as a puppet or slide valve may be substituted, although at present I prefer to employ a turning cock as it is not so liable to be injured by suddenly stopping the passage of water, and thereby producing the violent, shock, known as the water ram or hammer. 35

What I claim as my invention and desire to secure by Letters Patent is—

1. Combining with the issuing pipe and main cock, or two way cock, flat, or conical valve and leakage waste way; a piston and chamber, or a partly flexible chamber, emptying into, and receiving from, the issuing pipe, water, between the interval, of opening and closing the main; and leakage waste way. 40

2. I claim, the shutting force by hydrostatic pressure and gravity of the ordinary waste water, also the general arrangement of the moving parts by their gravity to favor the shutting force, substantially such 45 as herein described, and set forth.

JAMES COCHRANE.
